CLAIM

The ornamental design for an adapter for precision fluid dispenser tube, as shown and described.

DESCRIPTION

3. Adapter for precision fluid dispenser tube

3.1 is a front elevation view, the rear elevation view being a mirror image.

3.2 is a right side elevation view, the left side elevation view being a mirror image.

3.3 is a top plan view.

3.4 is a bottom plan view.

3.5 is a cross-sectional view, taken along line A-A as seen in 3.2.

3.6 is a perspective view.

3.7 is a reference view.

The dot-dash broken lines seen in reproductions 3.1-3.3, 3.6 and 3.7 represent the bounds of the claimed design. The dot-dash broken lines seen in the reproduction 3.5 cross-section view denote the boundary between the claimed and unclaimed portion. The broken line showing a dispensing tube in reproduction 3.7 is for the purpose of illustrating environment structure. All other broken lines are included for the purpose of illustrating portions of the adapter for precision fluid dispenser tube; the broken lines from no part of the claimed design.

1 Claim, 7 Drawing Sheets
